UNITED STATES PATENT OFFICE

CLIFFORD L. SNYDER, OF DETROIT, MICHIGAN, ASSIGNOR TO EVANS PRODUCTS COMPANY, A CORPORATION OF DELAWARE

DECKING DEVICE

Application filed August 4, 1930. Serial No. 472,917.

This invention relates to certain new and useful improvements in decking devices and has particular reference to the supporting or decking structure for a motor vehicle during shipment thereof, the decking devices being associated with the side walls of a freight car or the like, with the motor vehicle supported by its axle end on the decking devices, this invention being of the general character set forth in application filed by Clifford L. Snyder, on October 22, 1929, Serial Number 401,583 and embodies improvements thereover.

The primary object of the invention is to provide a head block carried by wall and floor attached bracing arms or members wherein the head is formed of sections embodying a cushioning element while the wall attached arms or members are of a resilient character for the purpose of absorbing shocks and jars incident to travel and to lessen liability of damage to the motor vehicle supported in the decking device.

A further object of the invention is to provide a decking device of the foregoing type wherein several parts thereof may be formed from inexpensive materials in the form of castings, one such material being aluminum alloy, it being found preferable to provide a nut of iron or steel for threaded engagement with an axle end or wheel hub with the nut interlockingly engaged with the head of the ejecting device for the purpose of eliminating injury to the axle end or wheel hub.

It is also the purpose of this invention to re-use the decking device as the same is capable of being easily collapsed and folded for transportation for further use.

It is a further object of the invention to provide decking devices of the foregoing character wherein a head or block for supporting a wheel hub or the like is mounted upon a decking structure comprising a floor anchored leg and wall anchored arm with cushioning or shock absorbing devices associated with the head and arms, or with either of said elements alone, the invention possessing advantages by the inward and downward compression of the wall attached arms to-

ward the head or block to offer greater resistance to upward thrust of the load.

A still further object of the invention is to provide a decking device comprised of a cushion head made of stamped or drawn metal combined with inexpensive wooden braces with shock absorbing elements associated with the head, this form of the device being of an inexpensive character which may, if desired, after a single use, be discarded, although the parts thereof may be easily separated for re-use if desired.

With the above and other objects in view that will become apparent as the nature of the invention is better understood, the same consists in the novel form, combination and arrangement of parts hereinafter more fully described, shown in the accompanying drawings and claimed.

In the drawings:

Figure 1 is a top plan view of a decking device constructed in accordance with the present invention, showing the floor supporting legs and the wall supporting arms carrying a head block in which a vehicle wheel hub is supported;

Figure 2 is a fragmentary side elevational view;

Figure 3 is a vertical cross-sectional view taken on line 3—3 of Figure 2, showing the decking device in front elevation;

Figure 4 is a front elevational view of the decking device in collapsed form;

Figure 5 is a front elevational view of the supporting head for the wheel hub;

Figure 6 is a side elevational view of the head;

Figure 7 is a vertical longitudinal sectional view of the head showing the elastic cushioning or shock absorbing member between nested sections of the head;

Figure 8 is a front elevational view of the nut disengaged from the head and employed for attachment to the wheel hub;

Figure 9 is an edge elevational view of the nut shown in Figure 8;

Figure 10 is a vertical cross-sectional view taken on line 10—10 of Figure 9, showing the groove at the edge of the nut to receive retaining pins on the supporting head;

Figure 11 is a fragmentary side elevational view of one of the wall attached arms for supporting the head;

Figure 12 is a longitudinal sectional view 5 of the wall attached arms illustrating the resilient character thereof;

Figure 13 is a cross-sectional view taken on line 13—13 of Figure 12;

Figure 14 is a fragmentary front elevational view 10 showing another form of decking device wherein the head is stamped or drawn from sheet metal, the floor anchored legs and wall attached arms are of wood and attached to straps carried by the head;

Figure 15 is a side elevational view;

Figure 16 is a top plan view;

Figure 17 is a vertical longitudinal sectional view, taken on line 17—17 of Figure 14, showing the shock absorbing cushion 20 insert in the head;

Figure 18 is a detail cross-sectional view taken on line 18—18 of Figure 15;

Figure 19 is a front elevational view, 25 partly broken away and shown in section of the wheel hub attaching socket associated with the head.

Figure 20 is a cross-sectional view similar 30 to Figure 18 showing the metal straps for attachment to the wall braces and floor leg at each side of the head formed of a single stamping having an intermediate connecting portion secured to the head;

Figure 21 is a fragmentary perspective view 35 of another form of the invention illustrating a decking device with a shock absorbing element in the head thereof;

Figure 22 is a perspective view of the shock absorbing element shown in Figure 21 and illustrating the metallic straps for anchoring 40 the same in the deck head;

Figure 23 is a perspective view showing the shipping hub cap assembled in a shock absorbing element which is in the form of a rubber cup; and

Figure 24 is a longitudinal sectional view 45 of the assembled shipping hub cap and shock absorbing element.

The reference character 15 designates a supporting head for an axle end or wheel hub 50 and is disposed in an elevated position for the decking of a motor vehicle. The head 15 is supported by a floor attached leg 16 and wall attached arms 17 as shown in Figures 1 to 3. While an axle may be supported at its end in 55 the head block 15, the invention herein illustrated is adapted for the support of the hub of the wheel 18, the threaded portion of which hub is engaged with a threaded portion of the head. The leg 16 is mounted at its lower end in 60 a socket member 19 anchored to the floor 20 while the outer end of the arms 17 that are upwardly and outwardly directed relative to the head 15 are detachably engaged with wall attached anchor plates 21 attached to the wall 22, the anchor plates 21 being provided with

a plurality of edge openings 21a to accommodate adjustment of the adjacent ends of the arms 17 when it is desired to vary the angularity thereof relative to the head 15.

The detail construction of the head 15 is 70 shown in Figures 5 to 10, the head comprising a pair of nested cone-shaped members 23 and 24 open at their larger ends with the closed ends 23a and 24a spaced from each other and connected by bolts or rivets 25 including elastic washers 26.

An elastic band 27 of frustoconical formation is disposed between the nested members 23 and 24 permitting limited 75 relative movement between these members and employed for the absorption of shocks or

jaws which fail in transmission to the vehicle supported in the decking device. The outer end of the inner nested member 23 is annularly enlarged as at 28 and the inner face of 80 the enlargement has adjacent angle features

providing a polygonal formation as indicated at 29 and shown more clearly in Figure 5.

Polygonal nuts 30 shown in Figures 8 to 10 are adapted to be disposed in the annular 85 enlargement 28 and prevented from rotation by the similarly formed socket 29 in the enlargement, the edge of the nut 30 being

grooved as at 31 and through which grooves, side pins 32 extend as will at once be obvious 90 from an inspection of Figures 5 and 7, the pins 32 extending through opposite sides of the enlargement 28 and forming an interlocking connection between the inner member

23 of the heads 15 and the nuts 30. A stud member 33 depends from the lower side of 95 the outer member 24 of the head for mounting in the upper end of the leg 16, while apertured lugs 34 pivoted upon opposite sides of the member 24 as at 34a have pivotal engagement with spaced apertured lugs 35 upon 100 opposite ends of the wall attached arms 17.

Figures 11 to 13 show the detail construction of the wall attached arms 17, the arms 105 17 being of tubular formation and having a

plug 36 anchored in one end thereof carrying the projected attaching lugs 35. A plug 37 is 110 slidably mounted in the other end of the arm 17, the inner end of the plug 37 carrying a rod 38 freely slidable through a block 39

provided with a central opening 40 for the passage of the rod 38, the block 39 being 115 anchored in the arm 17 by the cross-pins 41.

The extended end of the rod 38 is threaded for the reception of a nut 42 against which a stop washer 43 rests, a coil spring 44 sur-

rounding the rod 38 between the block 39 and stop washer 43 for tensioning sliding movement of the plug 37 in an outward direction.

A disk plate 45 is fixed to the rod 38 between the plug 37 and block 39 and a coil spring 46 surrounds the rod between the disk 45 and block 39 for tensioning the plug 37 during its 120 inward sliding movement relative to the arm 17.

It will therefore be seen that movements of the rod 38 and plug 37 is tensioned in oppo-

70

site directions and in lieu of the coil springs 44 and 46, cushion blocks may be employed, while a hydraulic construction may be substituted for the form of resilient mounting illustrated.

From the above detailed description of the invention, it is believed that the construction and operation thereof will at once be apparent, it being understood that the parts of the decking device may be constructed of inexpensive material, metallic castings or the like, but it is preferable to form the nuts 30, shown in Figures 8 to 10 of hardened metal such as iron or steel so that when the same is threaded upon an axle end or wheel hub, the threads of said part will not be mutilated. The nut 30 is first mounted upon the wheel hub and is then positioned in the enlargement 28 of the head 15 and there retained by the pin 32 passing through the edge grooves 31 of the nut 30 to form an interlocking connection between the nut and head. The elastic band 27 interposed between the nested sections 23 and 24 of the head, absorbs lateral shock and permits limited movement of the nested member 23 relative to the member 24, while the resiliently mounted plugs 37 in the arms 17 permit limited movements of the head 15 as a unit and act to absorb shocks and jars incident to travel so that liability of injury to a motor vehicle being transported by the decking device is greatly minimized. The decking device embodies shock absorbing features in the supporting head thereof and in the wall attaching arm and by such construction, injury to the parts of the decking device is also greatly reduced.

The decking device illustrated in Figures 1 to 13, is all metal construction, while the decking device shown in Figures 14 to 19 is of a combination of metal and wood, the head or block being formed of stamped or drawn sheet metal, while the floor anchored leg and wall attached arms are of wood, there-by providing an inexpensive construction, that may be discarded after a single use if desired. The sheet metal head as shown in Figures 17 and 18 comprises inner and outer nested conical sections 47 and 48 having walls 47a and 48a at the smaller ends thereof respectively secured together by a rivet 49 or the like which includes an elastic washer 50. The larger end of the inner conical section 47 is enlarged to provide a flange 51 of polygonal formation as shown in Figure 14, while the larger end of the outer section 48 is annularly flanged as at 52 to limit telescoping movement of the two conical sections 47 and 48, a shock absorbing gasket 53 being interposed between the two sections as shown in Figure 17. Angularly directed flanges or straps 54 are directed outwardly from the upper side of the outer section 48 for the attachment of wooden wall attached brace arms 55, while a pair of straps 56 depending

from the lower side of the outer section 48 in spaced relation are adapted for attachment to a floor anchored wooden leg 57. The nut 58 shown in detail in Figure 19 is constructed of harder material, such as iron or steel and has an edge groove 59 through which ends are adapted to pass, similar to the pins 32 for locking the nut 58 in the polygonal flange 51, the anchor pins passing through openings 51a. In this form of the invention, the shock absorbing element is alone associated with the head to which the vehicle axle or wheel hub is directly attached and such incident travel absorbed by the head without being transmitted to the vehicle.

In the form of the invention shown in Figure 20, the construction is modified from that shown in Figures 14 to 19 by the construction of the metallic straps for attachment to the wall braces and supporting leg. The wall brace attaching strap 54a and the leg attaching strap 56a at each side of the head that comprises the inner and outer sections 47 and 48 include intermediate connecting parts 60 of arcuate formation that are engaged with the adjacent side of the outer section 48 of the head and anchored thereto as at 61 by rivets or other connecting means, the other elements of the head construction being the same as disclosed in Figures 14 to 19.

In the form of the invention shown in Figures 21 to 24, there is illustrated a decking structure embodying supporting legs 62 arranged in inverted V-form with the upper ends connected by a head block 63, the upper ends of the legs 62 and head 63 being socketed as at 64 to form a seat for the support of the hub end of a vehicle wheel during shipment. A shock absorbing element for supporting the wheel hub is mounted in the seat 64 and includes a metallic shipping hub cap 65 having an internally threaded end 66 to be engaged with the hub of the wheel 67, the metallic cap 65 being seated in the elastic cup-shaped shock absorbing element 68 as illustrated. The assembled shipping cap and shock absorbing element are confined in the seat 64 of the deck head by the straps 69 and 70 having their ends 69a and 70a respectively attached to the deck head, the strap 69 preventing horizontal movement of the shock absorbing element while upward movement of the latter is prevented by the strap 70.

The several forms of the invention herein disclosed are generic to the idea of providing a cushioning or shock absorbing element in the head of a decking device, both in all metal constructions and in devices comprising wooden and metallic elements, the shock absorbing element positioned in the head of the deck absorbing shocks and jars incident to travel and preventing their transmission to vehicles being supported in the decking structures.

While there are herein shown and described the preferred embodiments of the invention, it is nevertheless to be understood that minor changes may be made therein without departing from the spirit and scope of the invention as claimed.

I claim:

1. A decking device for motor vehicles comprising a floor brace, a pair of wall braces and a head to which the braces are attached, said wall braces and head embodying shock absorbing elements.
2. A decking device for motor vehicles, comprising a head and anchor members, said head being formed of sections and a cushioning element interposed between the sections.
3. A decking device for motor vehicles, comprising a head and anchor members, said head being formed of sections a cushioning element interposed between the sections, and some of the anchor members embodying resilience in the lengthwise movement thereof.
4. A decking device for motor vehicles, comprising a head and anchor members said head being formed of sections, a cushioning element interposed between the sections, and some of the anchor members being formed of relatively movable sections having devices resiliently to resist such movements.
5. A decking device for motor vehicles comprising a head formed of nested conical sections, and a cushion shock absorbing element interposed between the sections.
6. A decking device for motor vehicles comprising a head formed of nested conical sections, connected together at their smaller ends, and a conical elastic shock absorbing band interposed between the sections.
7. A decking device for motor vehicles comprising a head formed of nested conical sections, and a cushion shock absorbing element interposed between the sections, a floor anchored leg depending from the head and wall attached shock absorbing arms connected to the head.
8. A decking device for motor vehicles comprising a head formed of nested conical sections, connected together at their smaller ends, and a conical elastic shock absorbing band interposed between the sections, a floor anchored leg depending from the head and wall attached shock absorbing arms connected to the head.
9. A decking device for motor vehicles comprising a head, a floor anchored leg and wall attached arms extending upwardly and outwardly from the head and including cushioning means to resist upward movement of the head and load carried thereby.
10. A decking device for motor vehicles comprising a head, and wall attached arms extending upwardly and outwardly from the head to resist upward movement of the head

and load carried thereby, and said arms including tensioned elements to absorb shocks before transmission to the head.

11. A decking device for motor vehicles comprising a head, a floor anchored leg and wall attached arms extending upwardly and outwardly from the head to resist upward movement of the head and load carried thereby, said arms including tensioned elements to absorb shocks before transmission to the head, and said head including a shock absorbing element effective in a direction of movement at an angle to the movement of the tensioned elements of the arms.

12. A decking device for motor vehicles comprising a head, a floor anchored leg and wall attached arms, and said head including a vehicle attaching member having side grooves and pins carried by the head interlocking engaged in the grooves to hold the member in the head.

13. A decking device for motor vehicles comprising a head, a vehicle attaching member removably mounted in the head and a shock absorbing element in the head.

14. A decking device for motor vehicles comprising a head, a floor anchored leg and wall attached arms, a vehicle attaching member removably mounted in the head, a shock absorbing element in the head, and shock absorbing elements in the wall attached arms.

15. A decking device for motor vehicles comprising an all metal construction including a head, a floor anchored leg and wall attached arms, and a shock absorbing element in the head.

16. A decking device for motor vehicles comprising a sheet metal head and wooden wall attached arms, a floor anchored leg, and a shock absorbing element in the head.

17. The combination with the head of a decking structure for the shipment of motor vehicles, of a shock absorbing element removably supported in the head of the decking structure.

18. The combination with the head of a shipping deck, of a shock absorbing element interposed between the head and supported part of a vehicle.

19. In a decking device of the character described, a decking structure for the support of a vehicle, and a shock absorbing element carried by the decking structure and directly associated with the supported part of the vehicle.

20. A decking device for motor vehicles comprising a deck head and a shock absorbing element in the head.

21. A decking device for motor vehicles comprising a deck head and a cup-shaped shock absorbing element set in the head for the support of a wheel hub.

In testimony whereof I affix my signature.
CLIFFORD L. SNYDER.
